Patented June 10, 1913.

UNITED STATES PATENT OFFICE.

EDWARD SEITZ, OF PEORIA, ILLINOIS.

VAPOR-LAMP.

1,064,018.

Specification of Letters Patent. Patented June 10, 1913.

Application filed September 12, 1910. Serial No. 581,716.

To all whom it may concern:

Be it known that I, EDWARD SEITZ, citizen of the United States, residing at Peoria, in the county of Peoria and State of Illinois, have invented certain new and useful Improvements in Vapor-Lamps; and I do hereby declare that the following is a full, clear, and exact description of the invention, which will enable others skilled in the art to which it appertains to make and use the same.

This invention relates to a lamp for burning vapors made from hydrocarbons and also for burning hydrogen or other illuminating gases, and therefore one of the objects of the invention is to arrange a lamp that may be used for either of these without the necessity of any structural changes to adapt it for such double use.

Another object is to produce a lamp of a new structure having a single burner for ordinary work, and a series of reserve burners supplied from the same source for heavy work or greater illumination.

Another object of the invention is to provide a lamp supplied with a hydrocarbon through a hollow wire system, using a common burner and a reserve burner that can be supplied from the same source that feeds the said common burner.

The invention further relates to certain details of structures as will be pointed out herein aided by the accompanying drawing in which:—

Figure 1 is a sectional elevation of the lamp. Fig. 2 is a plan of a burner-ring in part section showing a series of burner openings. Fig. 3 is a cross section of a valve and a longitudinal section of a part of the burner-ring shown in Fig. 2, and Fig. 4 is a side elevation of the said valve.

A indicates a pipe for suspending the lamp for instance from the ceiling, its upper end being suitably secured in a suitable hanger B, while to its lower end is attached a controlling valve C. Attached to and suspended from the said valve is a pipe D which has suspended from it, at its lower end, a fitting E which has a bore or passage F with which the pipe communicates. This bore terminates in an opening G at the side of the fitting into which is threaded a vapor discharge pipe H provided with a needle-valve J in control of what I shall term a nozzle shown at J'. Said fitting E is also provided with a bore K beneath the bore F but which is independent of it and whose

axis lies substantially horizontal and said bore is carried into and through an extension L which is a part of the said member E. Into said bore K opposite the extension L a pipe or conduit M is suitably secured, and communicating with said bore is a vertically arranged bore N in a depending extension O of said fitting E; this extension being provided with any usual burner P carrying a mantle Q, said burner being employed to heat the member E and the vapor discharge pipe H which constitutes a "vapor-generator," and also answering as a "pilot" burner to ignite the vapor at the mantles of a series of other burners to be described.

R is a hollow ring, Fig. 2, into and through which extends the outer or free end of the pipe or conduit M said end terminating opposite the needle valve J described to receive vapor from it. The said ring R has cast with it a portion S preferably having a cylindrical bore T (see Fig. 3) the axis of which is parallel to the bore of the extension L of the fitting E and which receives said extension, or at right angles to the bore of said ring. Snugly fitting the bore of said portion S is a cylindrical valve U shown clearly in Figs. 3 and 4 said valve being provided with openings V at two diametrically opposite sides to register with similar openings W in the wall S' of the said portion S as shown in Fig. 2. The end of the valve adjacent the extension L is open and communicates with the latter while its opposite end is closed as at 2. Suitable means is provided for rocking the valve as, for instance, an arm 3 to whose ends may be attached suitable chains or cords 4. The ring is provided with a series of burners 5 similar to the central one P described and the positions of these are indicated in Fig. 2 although other arrangements of them may be used.

The drawing shows an ornamental finish for the lamp which consists first of a bell-shaped canopy 6 whose lower end rests upon the ring R as shown in Fig. 1 but other means of supporting the same may be employed. Resting upon the upper end of said canopy is a member 7 upon which rests any ordinary shade 8 and slideable upon the pipe D is a spider 9 for holding the shade, and itself held in place by a collar 10 adjustable upon the pipe and secured for instance by a set screw 11. Preferably the

upper end of the canopy 6 snugly incloses the said pipe D in order to be maintained in a central position. While said canopy answers as an ornament its real purpose is one of utility in that it holds the heated air within it around the pipe D and fitting E; these parts constituting a vapor generator after the manner of lamps of this kind, whereby to vaporize the hydrocarbon but when ordinary gas is used the heat serves to raise its temperature thereby producing a whiter light.

12 indicates a hollow wire employed to conduct the hydrocarbon fluid to the valve C, said valve being in control of the fluid supply. When ordinary gas is used the pipe A may communicate directly with the valve and with the pipe system. It will be seen that my invention contemplates the use of 15 a battery of burners held in reserve and supplied from the same source as the main burner. In order to make this clear I shall now describe the operation of the lamp.

The valve C being in control of the hydrocarbon vapor, or common gas, as the case may be, admits said vapor or the gas to the valve J from which it is injected into the pipe or conduit M and thence to the burner P through the passages K and N. 20 The adjustment of said valve J provides for any desired flow of gas for the required illumination at the mantle Q and when not in use the light may be turned very low and left burning to provide sufficient heat to 25 keep the burner hot and the hydrocarbon at such a temperature as to produce the needed continuous flow of vapor; it being understood that when used for a hydrocarbon the generator composed of the lower end of the 30 pipe D and the fitting E as before described must be heated by some outside means in order to start the flow of vapor. When it is desired to light the reserve series of burners 35 which are also provided with mantles, the valve U, which has heretofore been closed, is opened so that the vapor or gas besides passing to the burner P is projected through the extension L of the fitting E into the valve U from whence it divides each 40 way into the ring R and distributes within the same and supplies the burners 5 mentioned; the latter being ignited from the said burner P. An adjustment of the valve J provides for a sufficient supply of vapor 45 or gas to properly feed all the burners to obtain the desired light. Any form of valve may be used, of course, in place of the valve U described that will answer the purpose and which will not allow leakage of gas 50 when only the central burner P is in use. I am aware that lamps used to burn gas have been employed in which there is a single burner and where a series of reserve burners have been used, the latter being ignited from the former but I am not aware 55

of a lamp that can be adapted to both hydrogen or other gas as well as a vapor manufactured from a hydrocarbon and particularly I am not aware of a lamp of the peculiar arrangement shown which includes 60 simplicity and cheapness of structure and compactness of form while providing for the advantages described.

I claim:

1. In a vapor lamp, the combination of 65 a conduit provided with a series of burners, a vapor discharge nozzle for introducing vapor to the conduit, a pipe connected to the nozzle and having a part cast with the said conduit, a generator burner suspended beneath the said part and having a position adjacent to the burners of the said series for lighting the same, a valve in control of the vapor discharge from the nozzle, and a valve in control of the said series of burners 70 and situated in said conduit between the said series and the generator burner.

2. In a vapor lamp, the combination of 75 a substantially ring-shaped conduit having a series of burners spaced apart upon the same, a conduit extending across the ring and having communication at one end with the ring and opening through the latter at its other end and open at the end outside the ring but closed from said ring, a vapor 80 pipe having a discharge orifice opposite the open end of the second named conduit, a generator-burner carried by the latter and communicating therewith, and having the vapor-pipe above the same for receiving 85 heat therefrom, and a single valve in the ring for interrupting communication of its 90 passage with the said series of burners and controlling all of the latter.

3. In a vapor lamp, the combination of 95 a substantially ring-shaped conduit having a series of burners mounted thereon, a vapor conduit extending across and through the passage of the ring at one side but closed 100 therefrom and having an open outer end outside the ring, the said vapor conduit communicating with the ring at its opposite side, a burner in communication with the said vapor conduit, and a valve between the said burner and the outlet from the 105 latter to the ring.

4. In a vapor lamp, a suspended fuel pipe, a conduit for vapor lying in substantially a horizontal position and having an integral extension suspended from the fuel pipe, 110 a vapor discharge nozzle as a part of the pipe and adapted to discharge into the conduit, a burner suspended beneath the vapor conduit and adapted for heating both it and the fuel pipe, a second vapor pipe connected with the first and provided with a series of burners, and a valve located in one of the conduits between the first said burner and the series of burners.

5. In a vapor lamp, the combination of 115

a fuel supply pipe, a hollow ring supported by it and provided with an opening at one side, a vapor supply pipe communicating with the opening and the ring, a valve within the ring to govern the flow of vapor from the pipe into the said ring, a burner communicating with the ring, and a generator connected with the fuel supply pipe and including an orifice lying opposite and discharging vapor into the said vapor pipe.

6. In a vapor lamp, the combination of a fuel supply pipe, including a generator and its discharge orifice, a hollow ring supported by it and provided with an opening at two places in its side, one of said openings being normally closed at the outer side of the ring, the other extending through both walls of said ring, a vapor pipe communicating with both openings and extending through one of them entirely through the ring to its outside and terminating opposite the said discharge orifice, a valve lying in the ring and in control of the passage of the same and that of the said vapor pipe, and a burner carried by and communicating with the ring.

7. In a vapor lamp, the combination of a fuel supply pipe, a hollow ring supported by it and provided with an opening at one side, a vapor supply pipe communicating with the opening and the ring, a valve within the ring to govern the flow of vapor from the pipe into the said ring, a burner communicating with the ring, a generator connected with the fuel supply pipe and including an orifice lying opposite and discharging vapor into the said vapor pipe, and a generator burner suspended from the latter.

8. In a vapor lamp, the combination of a fuel supply pipe, including a generator 40 and its discharge orifice, a hollow ring supported by it and provided with two openings in its sides, one of said openings being normally closed at the outer side of the ring, the other extending through 45 both walls of said ring, a vapor pipe communicating with both openings and extending through one of them entirely through the ring to its outside and terminating opposite the said discharge orifice, a valve 50 lying in the ring and in control of the passage of the same and that of the said vapor pipe, a burner carried by and communicating with the ring, and a burner beneath said vapor pipe.

9. In a vapor lamp, the combination of a fuel supply pipe, a hollow ring supported by it and provided with an opening at one side, a vapor supply pipe communicating with the opening and the ring, a valve with- 60 in the ring to govern the flow of vapor from the pipe into the said ring, a series of burners disposed around the ring, a generator connected with the fuel supply pipe and including a discharge orifice lying opposite 65 and to discharge vapor into the vapor pipe, and a burner beneath and supplied with vapor by the said vapor pipe and lying adjacent the said series of burners.

In testimony whereof I affix my signature, in presence of two witnesses.

EDWARD SEITZ.
